(57) **CLAIM**

The ornamental design for a DIN rail controller, as shown and described.

DESCRIPTION

3.-4. DIN rail controller

FIG. 3.1 is an isometric view of a DIN rail controller.

FIG. 3.2 is a top view of a DIN rail controller.

FIG. 3.3 is a bottom view of a DIN rail controller.

FIG. 3.4 is a left side view of a DIN rail controller.

FIG. 3.5 is a right side view of a DIN rail controller.

FIG. 3.6 is a front view of a DIN rail controller.

FIG. 3.7 is a back view of a DIN rail controller.

FIG. 4.1 is an isometric view of a second embodiment of a DIN rail controller.

FIG. 4.2 is a top view of a DIN rail controller.

FIG. 4.3 is a bottom view of a DIN rail controller.

FIG. 4.4 is a left side view of a DIN rail controller.

FIG. 4.5 is a right side view of a DIN rail controller.

FIG. 4.6 is a front view of a DIN rail controller.

FIG. 4.7 is a back view of a DIN rail controller.
